UNITED STATES PATENT OFFICE.

MAUDE B. WYATT, OF KILDARE, OKLAHOMA.

DESIGN FOR A SEED-PLANTER.

51,709.

Specification for Design.

Patented Jan. 29, 1918.

Application filed March 26, 1917. Serial No. 157,572. Term of patent 3½ years.

To all whom it may concern:

Be it known that I, MAUDE B. WYATT, a citizen of the United States, residing at Kildare, in the county of Kay and State of Oklahoma, have invented a new, original, and ornamental Design for Seed-Planters, of which the following is a specification, reference being had to the accompanying drawing, forming part thereof.

Figure 1 is a side elevation of a seed planter showing my new design.

Fig. 2 is a plan view thereof.

I claim:

The ornamental design for a seed planter, as shown.

MAUDE B. WYATT.

Witnesses:

MARY L. HOLLENBECK,
EVA B. RILEY.
